WATCHCASE

Filed Sept. 7, 1927

Inventor:
Daniel P. Lyons
by *Wm. H. Lyons*

UNITED STATES PATENT OFFICE

DANIEL P. LYONS, OF ELGIN, ILLINOIS, ASSIGNOR TO ILLINOIS WATCH CASE COMPANY,
OF ELGIN, ILLINOIS, A CORPORATION OF ILLINOIS

WATCHCASE

Application filed September 7, 1927. Serial No. 218,037.

This invention relates to a watch case of three pieces consisting of a case center, a bezel and a back. It relates more particularly to a bracelet type of watch case which is provided with two pairs of oppositely extending lugs adapted to support between them strap bars in the usual manner. The present improvements are directed especially to the formation of these lugs, to the manner in which 5 they are carried by the case center, to the cooperation between the mountings therefor and the case center itself, and to the method by which these several case parts are produced and assembled.

An exemplification of this invention is set forth in the accompanying drawing in the manner following:

Figure 1 is a view in elevation of the watch case in its entirety looking toward the bezel;

Fig. 2 is a side elevation of the case center;

Fig. 3 is a view in section taken on line 3—3 of Fig. 2;

Fig. 4 is a view in section taken on line 4—4 of Fig. 1;

Fig. 5 which is a view similar to Fig. 3 shows a modification in the lug construction;

Fig. 6 is a view in elevation looking toward the plate forming the bottom of one of the case center components;

Fig. 7 is a side elevation of the two case center components in assembled relation;

Fig. 8 is a similar view of the smaller of these components;

Fig. 9 is an edge elevation of one of the bars 35 which is secured to an edge of the case; and

Fig. 10 is a side elevation thereof.

The present watch case is of the three piece type comprising a case center A, a bezel B, and a back C. The bezel and back may be

40 secured to the case center in any approved manner as by a snap connection.

The case center or movement ring herein shown is formed of two components each substantially a duplicate of the other except for 45 size. As shown best in Fig. 6, each component

consists of a plate 11 with upstanding marginal flanges 12. In the plate is formed a central aperture 14 through which the watch movement may pass when being moved into or out of its mounting. The two components 50 of the case center are of such size relatively that the flanges of one may just fit within the flanges of the other. When so related the two plates 11 define between them a double walled space wherein a watch movement may 55 be received and held.

The outer face of each plate may be suitably configured to provide a means for establishing a snap connection with the associated bezel B or back cover C. This may take the 60 form of a shoulder 17 (see Fig. 7) which is provided on the larger of the two components. When the smaller component is fitted within the other, a small edge portion will remain 65 protruded therefrom to constitute a second shoulder 18. In this manner, I may provide a means for establishing snap connections with both the bezel and back cover, each of which may be of the usual kind.

Formed through the flanges of the two 70 case center components are registering holes 19 and 20 respectively. These are located preferably in the longitudinal sides of the case (see Fig. 3). To connect these two parts of the case center inseparably, I utilize a pair of 75 bars 21 one extended along each of the longitudinal edges of the case center, and each provided with inwardly extending pins 22, one for each of the holes 19 and 20. The pins 80 which are entered through these holes protrude slightly beyond the inner face of the inner flange 12, so as to be exposed for swaging. The pins thus constitute rivets which connect together the two case parts and also 85 secure thereto the two bars 21 in the manner best shown in Fig. 3. The bars may be desirably ornamented or embossed, as suggested in the drawing, so as to enhance the 90 appearance of the case and having a substan-

tial surface in contact with the sides of the case center which serves to appreciably reinforce the finished article. In addition the opposite ends of the bars are so formed and extended as to protrude in parallelism beyond the ends of the case, thus providing lugs 23 in each of which is formed a hole 24. These lugs thus constitute mountings for bars (not shown) to which the ends of suitable straps or bracelets may be attached.

Certain deviations may obviously be made from the construction hereinbefore described without departing essentially from this invention. One such modification is suggested in Fig. 5 wherein I have utilized four lugs 25, each separately formed, in lieu of two bars the ends of which provide the desired lugs. In this construction the lugs may be appropriately formed for mounting upon the ends of the case, and preferably each is provided with a tapering foot 26 which emerges with the contour of the case center. The lugs so formed are provided with pins 22 furnishing rivets by which to connect with the case center and join inseparably the two components thereof in the manner already explained.

The present invention is advantageous in several respects. It may be practiced by die operations which produce a case center of two parts adapted, when united, to furnish a mounting for a watch movement. In addition it provides for a secure and inseparable connection between the parts of the case center so formed, and at the same time provides the lugs which are necessary for the support of a bar to which a bracelet or strap is attached. In the operations of producing the present case, the two components of the case center are first blanked out and formed up, then interfitted, and lastly connected by swaging of the pins which extend laterally from the lug bars, these latter elements being themselves secured to the case center by the same means.

I claim:

1. A watch case in which is comprised a case center formed of two parts presenting double side walls in which are registering holes, and lug bars substantially engaging the sides of the case and extending from opposite ends thereof having means passing through the holes of both side walls and engaging with the inner face thereof to prevent withdrawal therefrom, the lug bars being thereby secured in place and the two walls of the case center being locked inseparably together.

2. A watch case in which is comprised a case center having double side walls through which are formed registering holes, bars extended along and in contact with the outer side walls, pins extended laterally from the bars through the proximate holes of the walls and upset against the inner faces thereof

whereby to inseparably lock the walls and bars together.

3. A watch case in which is comprised a case center formed of two parts each having an apertured plate with an upstanding marginal flange, the flange on the one part being received within the flange of the other whereby the two plates are spaced apart a desired distance, there being registering openings through the adjacent marginal walls along opposite sides of the case center, and bars mounted in side contact with the outer marginal side walls and carrying laterally extending pins passing through the registering holes thereof, the pins being upset against the inner marginal walls and furnishing an inseparable connection by which the two case center parts and bars are held in unitary relation.

4. A watch case in which is comprised a case center formed of two complementary parts each comprising a plate with upstanding marginal walls, the one part being adapted to present its walls inside the marginal walls of the other with the plates in spaced relation, there being formed in opposite marginal side walls registering openings, and a pair of bars adapted to be fitted against the sides of the case center and over the openings through the marginal walls thereof, the ends of the bars being extended beyond the ends of the case and forming opposite pairs of lugs, and pins extending laterally from the bars for passage through the openings in the marginal side walls of the case and adapted to be secured thereto.

5. A watch case in which is comprised a two-part case center having double side walls, bars substantially contacting the outer side walls and having portions extending therebeyond, and means rigidly securing the bars to both walls of the case center.

6. A watch case comprising interfitted case center members providing double side walls, and side edge embracing and reinforcing members permanently secured to both walls of the case center and extending therebeyond, said extending portions providing spaced bracelet receiving lugs.

7. A three piece watch case in which is comprised a two-part case center having double side walls provided with registering holes, bars having a substantial surface in contact with the sides of the case and projected from opposite ends thereof, said bars having means extending through the registering holes in the side walls of the case to connect the bars and the parts of the case center inseparably together.

8. A watch case in which is comprised a case center formed of two interfitted parts presenting double side walls with a plurality of spaced registering openings therethrough, and outer wall forming bars having portions conforming in contour with the external sur-

faces of, and of substantially the same width as said side walls, said contour conforming portions of the bars being in contact with said surfaces, and means on the bars received through the openings in the side walls to provide an inseparable connection between the bars and the two interfitting parts of the case center.
